(57) **CLAIM**

The ornamental design for a finial for light fixture, as shown and described.

DESCRIPTION

FIG. 1 is a perspective view of a first embodiment of the finial for light fixture of the present design;

FIG. 2 is a front elevation view thereof;

FIG. 3 is a right side elevation view thereof, the left side elevation view being a mirror image of the claimed structure;

FIG. 4 is a top plan view thereof;

FIG. 5 is a bottom plan view thereof;

FIG. 6 is a rear elevation view thereof;

FIG. 7 is a perspective view of a second embodiment of the finial for light fixture of the present design which differs from the first embodiment only in proportions. It is understood that all of the other surfaces being the same as in Embodiment 1 except for the identified difference; and,

FIG. 8 is a perspective view of the first embodiment identical to FIG. 1 except for the addition of unclaimed environmental structure.

The broken line showing is for illustrative purposes only and forms no part of the claimed invention.
